US00D623523S

(12) **United States Design Patent**
Toh et al.

(10) **Patent No.:** **US D623,523 S**
(45) **Date of Patent:** ** *Sep. 14, 2010

(54) **CONTAINER**

(75) Inventors: **Kiat Cheong Toh**, Forest Hills, NY (US); **John Lamb**, Pewsey (GB); **Will Maskell**, Marlborough (GB); **Alan Whiting**, Penrith (GB); **Tom Walton**, Marlborough (GB); **Corinne Elstow**, Marlborough (GB)

(73) Assignee: **Colgate-Palmolive Company**, New York, NY (US)

(**) Term: **14 Years**

(21) Appl. No.: **29/339,423**

(22) Filed: **Jun. 30, 2009**

(51) LOC (9) Cl. **09-01**

(52) U.S. Cl. **D9/516**; D9/522; D9/575

(58) **Field of Classification Search** D9/516, D9/520, 522, 523, 526, 530, 543, 544, 545, D9/549, 550, 551, 552, 563, 564, 565, 571, D9/575; 215/381-385

See application file for complete search history.

(74) *Attorney, Agent, or Firm*—Amy M. Fernandez

(57) **CLAIM**

The ornamental design for a container, as shown and described.

DESCRIPTION

FIG. 1 is a front, right, perspective view of a container showing our new design;

FIG. 2 is a front, left, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of a pour spout, label with helical design and bottom portion of a container is included for the purpose of illustrating only and forms no part of the claimed design.

1 Claim, 7 Drawing Sheets
